(57) **CLAIM**

The ornamental design for a surgical template for distal extension, as shown and described.

DESCRIPTION

FIG. 1 is a rear perspective view of a surgical template for distal extension embodying my design;

FIG. 2 is a front perspective view thereof;

FIG. 3 is a front view of FIG. 2, the rear view being a mirror image of the front view;

FIG. 4 is a right side elevational view thereof, the left side elevational view being a mirror image of the right side elevational view;

FIG. 5 is a top plan view thereof; and,

FIG. 6 is a bottom plan view thereof.
